UNITED STATES PATENT OFFICE.

JOHN J. HEYS, OF LYNN, MASSACHUSETTS, ASSIGNOR TO MANUFACTURERS MACHINE COMPANY, OF MONTCLAIR, NEW JERSEY, A CORPORATION OF NEW JERSEY.

SOLE-LAYING MACHINE.

No. 878,391.

Specification of Letters Patent.

Patented Feb. 4, 1908.

Application filed April 19, 1906. Serial No. 312,558.

To all whom it may concern:

Be it known that I, JOHN J. HEYS, a citizen of the United States, residing at Lynn, in the county of Essex and Commonwealth of Massachusetts, have invented an Improvement in Sole-Laying Machines, of which the following description, in connection with the accompanying drawings, is a specification, like letters on the drawings representing like parts.

This invention relates to sole laying or leveling machines of the type wherein the sole is acted upon by a form shaped to correspond with the desired shape to be given to the whole or any part of the shoe sole. Machines of this kind as ordinarily constructed, are known as direct pressure machines.

Prior to my invention the most common construction has been to mount these forms rigidly in the machines; that is, incapable of any rolling or adjusting motion, such as would permit the same to conform or adapt themselves to the level, pitch or inclination of the last upon which the sole is mounted.

Since there is much inequality in lasts, particularly when of wood, as well as in the build of the shoe, it is rarely the case that a sole is evenly presented to the form that is to act upon it. Consequently, either the shoe or the last or both, are subjected to unequal damaging pressure, or else the work is shifted, distorted, or otherwise disarranged in the effort to adapt itself to the immovable or rigidly mounted form.

My invention comprises an improved means for movably and preferably universally mounting the form for free adaptation or conformation to the sole presented to it, so as to give to the sole the required contour or shape without undue or improper inequality of pressure or tendency to shift the work or damage the last.

My invention also contemplates accessory devices for use in connection with the above, all of which will be best understood from a description of the best embodiment of my invention that I have as yet put into use and which is shown in the accompanying drawings, wherein,—

Figure 1 is a side elevation of the machine containing such embodiment; Fig. 2, a front view thereof; Fig. 3, a detail of a part of the machine head in which the form is

mounted; Fig. 4, a vertical section on the dotted line 4—4, Fig. 3; Fig. 5, a view similar to Fig. 3, but viewed from the opposite side; Fig. 6, an under side or plan view of Figs. 3 to 5, inclusive, the form being omitted.

In the particular embodiment of my invention selected for illustration herein and shown in the drawings, referring first to Figs. 1 and 2, the machine therein shown is substantially the same as that illustrated in my U. S. Patent No. 581,662, dated April 27, 1897, to which reference may be had, like reference letters representing like parts. Since the construction of such machine is well known in the art, it is unnecessary to give in detail the construction or mode of operation thereof other than to call attention to the fact that the machine is a twin machine comprising the two last supporting tables which are caused to move inward and outward and to rise and fall alternately to present their respective shoes thereon to forms *g* depending from the head *C* at the top of the machine. In said Patent No. 581,662 the forms *g* are rigidly or immovably held in and by said head, except that they are supported by springs *m*, which permit them to give somewhat as the last supported shoe rises from beneath. Referring to Figs. 3 to 6 of the accompanying drawings, the corresponding form *g*, is, in accordance with my invention, mounted in such a manner that it may adapt itself to the sole and last presented to it. The head *C*, as in said patent, is provided with a housing for the spring *m*, the latter at its upper end being seated against a plate *n* on the end of an adjusting wheel, *o*, by means of which the abutment plate *n* may be adjusted to vary the tension of the spring. At its lower end (see Fig. 4) said spring is seated upon a head or form carrier *1*, fast upon the end of a rod 2, that rises through said spring and adjusting nut and at its upper end has clamped upon it the stop nut 3. In the bottom face of this form carrier *1*, is a semi-spherical recess for a complementary shaped boss 4, on the form supporting plate 5. This plate 5 has a vertical central aperture for the headed supporting device 6, that is screwed into the bottom of said rod 2, the opening in the said plate above the said supporting device being larger than the said device to

permit of perfectly free or gyrating movement of said plate relative to said form carrier. In other words the plate is universally mounted upon the under side of the 5 form carrier by means of the semi-spherical recess and boss, which constitute one form of ball and socket or universal connection between the two.

The plate 5 has a front to back dove-tailed groove 6^a, see Fig. 5, to receive a correspondingly shaped rib upon the back or top of the form 9, and by means of which said form may be slid into and out from position under and secured to the said plate. 10 The form is positioned and there held by a locking device 7, pivotally connected to said support at 7^a, and adapted to swing down over and to coöperate with an adjusting screw 8 on the form, which adjusting screw 20 is of a length accurately to fit between the hooked end of said locking device and the hub thereof, whereby said form is held against movement in either forward or backward direction, yet is adjustable without interfering with its retention as described, by turning said screw in its support on said form.

When a last with a lasted shoe thereon with a sole positioned or preliminarily laid 30 is brought up to the form in the operation of the machine, the moment the sole or a part thereof engages the form the latter responds to the approaching sole and the last beneath it and without substantial resistance, positions or adapts itself to the approaching last. Thus, if the last is one-sided or its spindle hole is out of alinement, or if for any other reason the sole is presented in an irregular or abnormal position to the 40 form, the latter will conform thereto, instead of requiring the sole and its last to do the conforming; and this conformation of the form takes place without any sacrifice of effective pressure, and without any shifting 45 action imparted to the sole; for obviously, the shape of the form will be imparted to the sole, or the pressure will at all points of the sole be more properly imparted thereto, as well when the form is conforming, as when 50 it is rigid. In fact, a more accurate and uniform pressure is possible with a conforming form, such as here described, than would be possible were it rigid with no possibility of the sole surface conforming to it; which is 55 practically the case where the entire shoe, last, jack or form and its carrier must be conforming. Of course, all variations in lift are compensated for by compression of the spring *m*, as in the earlier type of machine, the conforming action of the form being additional to this vertical yielding action.

It will be noticed that the center of the universal connection which, in the embodiment shown in the drawings, is at or about 60

the point marked 9, is so close to, in fact being shown as substantially coincident with, the deepest part of the adjacent form surface, that the rolling or conforming action of the form does not tend to give any appreciable bodily creeping sidewise or longitudinal movement of the form with reference to the sole, so that there is no tendency to displace the sole on the shoe, nor the shoe on its last. It is desirable with a conforming form of this 70 type that means be provided for centering it always in normal position after each effective action; otherwise the form might be displaced considerably at one action or operation, and if left there, would be presented 75 improperly to the next shoe to be operated upon.

For the purpose of returning the form always to normal position when freed from pressure, I have provided the carrier 1, with a plurality, preferably four recesses, for the restoring pins 10, each rounded at its lower end by preference and adapted to press upon the top of the form carrying plate 5. These pins are headed at their upper ends to prevent them from dropping out at any time and upon their headed ends are seated springs 11, which at their upper ends are in turn seated upon a ring-like plate 12, secured upon the top of said head 1. These springs 90 being of substantially equal tension act normally to center or balance the plate 5 and its form in normal or central position so far as its level is concerned, although said pins are perfectly free to yield singly or together, as 95 may be necessary to bring the form into position to conform to the approaching last and sole thereon. The form 9 is also free to swing in a horizontal plane to adapt itself to the alinement of the last presented to it and to 100 restore the alinement to normal after each operation, I have provided the plate 5 (see Figs. 4 and 5) at its end opposite the locking device 7 with a projecting ear 12^a, which stands between the depending arms 13, of 110 two bell crank levers pivoted at 14 upon the said head 1 and having their inwardly directed ends segmentally geared and meshed to cause equal opposite movement of said two arms. A spring 15 tends to draw said 115 depending arms normally towards each other and towards the opposite side of said ear to center the latter between them. Obviously, any deflection of said ear to one side or the other due to any adjustment of the alinement of the form to that of an approaching last will cause one of said arms to be swung away from its normal position, causing thereby equal and opposite movement of the mating arm. As soon as the said form is freed 120 125 the spring 15 will draw the two arms together, thereby centering the ear between them and restoring the form to its normal position.

My invention is particularly useful in connection with either sole laying or leveling 130

upon wood lasts, which vary greatly in size, shape and in the alinement of the spindle holes, although it has other advantages that will be apparent to those skilled in the art.

5 I claim--

1. A machine of the class disclosed comprising a shoe support, a form support, supporting means for the latter constructed and arranged to permit said form support to adjust itself freely to the angular and alinement 10 position of the work presented to it, and means to restore said form support angularly and alinedly to predetermined relation to said work support after each operation.
- 15 2. A machine of the class disclosed comprising a shoe support, a form support and a universal mount for the latter having its center of motion substantially at the form surface and means disposed about the universal 20 mount tending to restore the parts to central position when free to move.
- 25 3. A machine of the class disclosed comprising a shoe support, a form support, and means to cause relative approach to the same 30 means permitting free alinement adjustment of said form support to the opposed shoe support and connected segmental gear restoring devices to restore said alinement to predetermined relation to said shoe support after each operation of the machine.
- 35 4. A machine of the class disclosed comprising a shoe support, a form support and means to cause relative approach of the same, the form carrier 1 and the universally mounted form support 4, the centering pins 10 and gear restoring devices 13.
- 40 5. A machine of the class disclosed comprising a shoe support, a form support and means to cause relative approach of the same, the universal connection 1—4, and the supporting pin 6, the spring *m* and adjusting de-

vice *o*, together with the centering and restoring devices 10 and 13.

6. A machine of the class described comprising a shoe support, a form support, 45 means to cause relative approach thereof, a universal mount for said form support, and centering means to restore said form support, both longitudinally and transversely to predetermined position after each operation of 50 the machine.

7. A machine of the class described comprising a shoe support, a form support, means to cause relative approach thereof, a universal mount for said form support, and 55 centering means to restore said form support, both longitudinally and transversely to predetermined position after each operation of a machine, said centering means comprising a series of spring actuated centering pins 60 disposed about the universal mount.

8. A machine of the class described comprising, in combination, a shoe support, a form support, a universal mount for said form support, and a carrier provided with a 65 series of spring pressed pins bearing on the form support for returning the same to normal position.

9. A machine of the class described comprising, in combination, a shoe support, a 70 form support, a universal mount for said form support, a carrier provided with a series of spring-pressed pins bearing on the form support for returning the same to normal position, and a support centering device. 75

In testimony whereof, I have signed my name to this specification, in the presence of two subscribing witnesses.
